Primary Examiner — Kelley A Donnelly(74) *Attorney, Agent, or Firm* — MP Patents, LLC(57) **CLAIM**

The ornamental design for a barricade post as shown and described.

DESCRIPTION

FIG. 1 is a perspective view of the barricade post according to my new design.

FIG. 2 is a rear view thereof.

FIG. 3 is a front view thereof.

FIG. 4 is a right-side view thereof.

FIG. 5 is a left-side view thereof.

FIG. 6 is a top view thereof.

FIG. 7 is a bottom view thereof.

FIG. 8 is a perspective view of the barricade post in use with rails and other barricade posts; and,

FIG. 9 is a perspective view of the barricade post in use with rails and other barricade posts with some rails folded down. The broken lines shown in the figures represent unclaimed subject matter of the barricade post and form no part of the claimed design. The broken lines in the figures depicting rails and other barricade posts are to show environment and form no part of the claimed design.

1 Claim, 7 Drawing Sheets(56)
